US0D1028770S

(12) United States Design Patent (10) Patent No.: US D1,028,770 S
(45) Date of Patent:  May 28, 2024

(54) WATCH DIAL

(71) Applicant: PARMIGIANI FLEURIER SA,
Fleurier (CH)

(72) Inventor: Michel Parmigiani, Fleurier (CH)

() Term: 15 Years

(21) Appl. No.: 35/516,589

(22) Filed: Mar. 16, 2022

(80) Hague Agreement Data

Int. Filing Date: Mar. 16, 2022

Int. Reg. No.: DM/219643

Int. Reg. Date: Mar. 16, 2022

Int. Reg. Pub. Date: Mar. 17, 2023
